UNITED STATES PATENT OFFICE.

ALVAH S. FRENCH, OF NEW YORK, N. Y.

SHOE-FASTENER.

SPECIFICATION forming part of Letters Patent No. 444,824, dated January 20, 1891.

Application filed January 25, 1890. Serial No. 338,080. (No model.)

To all whom it may concern:

Be it known that I, ALVAH S. FRENCH, a citizen of the United States, residing in the city, county, and State of New York, have invented certain new and useful Improvements in the Means of Fastening Shoes; and I do hereby declare the following to be a full, clear, and exact description of the same, which will enable any one skilled in the art to which the said improvements appertain to make and use the same.

My invention relates to that class of fastening devices for shoes which consist generally of a series of clasps, clamps, or slides secured to a strap at intervals along its length, and engaging with ribs, strips, runners, or enlarged edges upon the flaps of the opening in the shoe, said clamps serving to close the said opening by being slid along such ribs, strips, runners, or enlarged edges.

A great difficulty in the devices of the class described has been that the successive clasps would not reliably engage with the ribs or enlarged edges as the strap was pulled up along said ribs or edges to close the opening in the shoe. To obviate this difficulty it has been proposed that the lower end of the strap be secured to the shoe below the opening and the clasp slid up and down the enlarged edges or ribs without becoming disengaged from them; but this would result in having the strap and clasps pushed together in a very clumsy way at the bottom of the opening when the shoe is taken off, and would make it difficult to withdraw the foot.

The object of my invention is to provide a means whereby in such a fastening device the successive clasps or clamps will be started upon and will reliably engage with the enlarged edges or ribs upon the flaps as the strap is drawn up along said edges or ribs without necessarily having said strap secured to the shoe at any point.

My invention is shown by the accompanying drawings, forming part of this specification, in which similar letters denote similar parts.

Figure 1 is a perspective view of the upper and flaps of a shoe, showing the strap D, the clasps E E, and the guide H. Fig. 2 is a cross-section of Fig. 1 through the line X X. Fig. 3 is an enlarged view of a part of Fig. 1,

with the guide-band detached on one side and thrown back so as to show the ends T T and the opening S. Fig. 4 is a perspective view of the strap D with the clasps E attached.

A is the upper of a shoe.

B is the opening.

The edges C C of the shoe-flaps are each suitably enlarged beyond the thickness of the shoe-upper and its lining either by fastening a strip of leather or other suitable material upon said edge or under it by suitable means or in some other suitable way. The enlarged edges C C are shaped in cross-section so as to conform to the shape in cross-section of the recesses or grooves, hereinafter described, in the clasps or clamps E. E is a clasp or clamp made of sheet metal or other suitable material, having in transverse section substantially the shape of a Z. This clasp is provided with two enlarged recesses or grooves, one above and one below the diagonal part of the Z, said recesses or grooves having openings J in the side, which openings are large enough to admit the part of the flaps adjacent to the enlarged edges or ribs C C, but too small, relative to the greatest thickness of said enlarged edges, to permit their withdrawal in the direction of the tension or strain upon the flaps of the shoe.

D is a strap of leather or other suitable flexible material, having the clasps E secured to it at intervals along its length by sewing, riveting, or other suitable means. In the drawings a rivet R is shown. The lower ends of the edges or ribs C are left free and may be finished off in a point T T. A small opening S may be left in the upper at one of the ends T, by which the lower part of the clasp E, when properly guided, will pass beneath one of the enlarged edges or ribs C, while the upper part will pass over and outside the other enlarged edge, the clasp E thus engaging with the edges C C.

To insure the successive clasps E E being properly started on the enlarged edges C C and thus reliably engaging with the same, I employ a guide-band consisting of a strip of leather or other suitable material secured by suitable means to the shoe-upper on either side of the ends T T of the enlarged edges C C and forming a low arch over said ends.

The guide-band extends longitudinally from a short distance above the ends T T to some distance below them. The arch formed by the guide-band is of such a height above the 5 surface of the upper as just to allow the strap D, with clasps E attached, to be drawn readily under it, and the width of the arch tapers from just the width of the clasp E, where the arch covers the points T T, to a broad 10 flaring mouth K at the lower edge of the arch or guide-band. In practice it will not be found necessary to remove the strap D entirely upon taking the shoe off, but the uppermost clasp may be left engaged with the edges 15 C C. Should, however, the strap D have been entirely removed, it may be started again by passing the tab L under and through the guide-band or arch H. The tab being through the arch is pulled upward. As each successive 20 clasp E passes into and under the arch or guide-band H, it will be drawn into position by the tapering form of the arch, and will slip onto and engage with the enlarged edges C C, being prevented from diverging from its 25 proper course by the close-fitting walls of the arch or guide-band H. I thus make fastening devices of the class herein described practicable and certain in action without the inconvenience resulting from attaching one end 30 of the strap D immovably to the shoe.

I do not limit myself to any particular form of clasp or slide, having chosen the one herein described for convenience. Nor do I limit myself to the particular form of runners shown, 35 consisting of enlarged edges on the flaps; but

I desire to cover all devices of the class described in connection with the guide-band or arch H.

I do not in this application claim, broadly, a fastening device consisting of a series of 40 clasps or slides secured to a strap at intervals along its length and engaging with ribs or runners upon the flaps of the shoe; but

What I do claim as new, and desire to secure by Letters Patent, is— 45

1. In a shoe-fastening device having a strap, sliding clasps, and runners, a guide-band secured to the shoe on either side of the lower ends of the runners and forming an arch over said ends, said arch being shaped to guide the 50 successive clasps onto the runners as the strap is drawn into place, substantially as and for the purpose described.

2. In a shoe-fastening device having a strap with sliding clasps attached and runners on the flaps of the shoes with which the clasps engage, a guide-band secured to the shoe and forming an open arch over the lower ends of the ribs or runners, said arch being of suitable height above the surface of the upper, so 55 that the strap with clasps attached will pass under it, and tapering in width so as to guide the successive clasps onto the runners and insure their reliably engaging with the same when the strap is pulled into place, substantially as shown and described. 60

ALVAH S. FRENCH.
